POCKET PYROPHORIC LIGHTER

Arthur Goldberger, Vienna, Austria, assignor to
Arnold Liebling, Rockford, Ill.

Application July 27, 1937, Serial No. 155,848

2 Claims. (Cl. 67—7.1)

This invention relates to a pocket pyrophoric lighter, of the type in which the operation of an actuating member brings about, in succession, the opening of the cover normally fitting closely over the inflammable wick of the lighter, and rotation of the friction wheel co-acting with a pyrophorous body to produce the igniting spark, and consists essentially in so mounting the said cover and coupling the same with the moving parts of the actuating mechanism that, in opening, the cover is first moved axially with respect to the position of the wick in the lighter and then laterally and outwards. In this manner, as compared with the known types of pyrophoric lighter with merely pivoted cover, the result is achieved that when the cover is closed the extinguisher fits tightly over the end of the wick holder or tube, while when the cover is open the whole of the space above the flame is free and untrammeled.

In accordance with the invention the cover is mounted on a vertical rod which is guided, by means of a guide pin, in a groove in a sleeve, and coupled with the actuating member by a lever arrangement which lifts it out of the sleeve, so that it is first lifted clear of the wick and then swung outwards through an angle of about 90°.

A form of construction of lighter according to the invention is shown, on a magnified scale, by way of example, in the accompanying drawing, in which:

Fig. 1 shows the lighter according to the invention in side elevation, in the closed condition with the side wall broken away to disclose the actuating mechanism.

Fig. 2 shows the same in plan view.

Fig. 3 shows the same lighter in the open condition, as after operation, again in side elevation with the near side wall for the greater part broken away.

Fig. 4 is a plan view of the open lighter.

Referring to the drawing, in which like parts are denoted by like reference numerals throughout, the pyrophoric lighter according to the invention consists, in a known manner, of a housing or casing part 1 in the interior of which is stowed the fuel tank 2 which is generally filled with wadding or the like, and from which the wick 3 extends loosely out of a small conical extension 4. The spring-loaded stick of pyrophorous material 5 is guided in a tubular holder extending from the bottom to the top of the fuel tank, and bears against the friction wheel 6 mounted on top of the tank. The side walls 7, 7₁ of the casing 1 extend beyond the end of the wick, and are provided

with air admission apertures 8, and thus serve to protect the flame from wind. Adjacent the fuel tank 2 and extending along the side wall of the casing there is disposed a round section tube 10 having at the lower end a slot 9 which is first straight and then, further up, of helical shape. Into this tube there is inserted a round section rod 12 which is provided at the lower end on each side with a guide pin 11, and to the upper end of which there is secured the cover 13 of the lighter, the said pins 11 being adapted to engage in the slot 9 in the tube 10. On the under side of the cover 13 there is secured the extinguisher 14 which is so dimensioned that, when the cover is in the closed condition, the extinguisher not only reaches down to the top of the tank 2 but also fits closely against the conical surface of the extension 4 on this tank.

In place of a front wall to the casing there is a thumb piece 23 which is pivoted at the lowermost point 15 between the two casing side walls 7, 7₁, and which is stressed by a spring 16 tending to force it outwards. The upper end of the thumb piece 23 is bent over inwards at an angle and provided on either side with a pin 18. These pins 18 engage in parallel slots 19 in a two-armed channel-section lever 20 which is pivoted about the axis 6₁ of the friction wheel, and of which the free arms are articulated with their outer ends 21 to a link 22 attached to the upper end of the rod 12 to which the cover 13 is also attached.

The thumb piece 23 is provided with an inwardly extending rack 25 which meshes with a pinion 24 coupled for rotation with the friction wheel 6.

The mode of operation of the described pyrophoric lighter is as follows: When the cover 13 is closed (that is to say when the lighter is in the inoperative condition) the thumb piece 23 juts out somewhat beyond the contour of the lighter (see Fig. 1), the vertical rod 12 on which the cover 13 is mounted is in the completely lowered position, and the pins 11 are at the bottom of the slot 9. To operate the lighter the thumb piece 23 is pressed inwards (Fig. 2) against the action of the spring 16. Through the intermediary of the pin 18 the lever 20 is thereby tilted so that its other end moves upwards. This movement is imparted to the link 22 which begins by lifting the rod 12 and with it the cover 13, and that as long as the pin 11 on the rod 12 travels in the straight portion of the slot 9. As soon as the stud 11 engages in the helical portion of the slot 9 the rod 12 and with it the cover 13 becomes rotated through 90° (Fig. 4). Previously, namely at the

beginning of the movement of the thumb piece 23, the rack 25 on the thumb piece engages in the pinion 24, rotating this latter and with it the friction wheel 6, with the result that sparks are generated which ignite the uncovered wick. As long as the thumb piece 23 remains in the pressed-in position the cover 13 remains open. When the thumb piece 23 is released it is returned by the spring 16 into its initial position, all the other parts of the mechanism being thereby also restored into their original positions.

I claim:

1. In a pyrophoric lighter having an inflammable wick and a pyrophorous body, a cover enclosing said inflammable wick in the closed position of the lighter, a friction wheel bearing against said pyrophorous body, a movable actuating member and means connected with said member, said cover and said friction wheel and operable upon the actuation of said member to first move said cover axially in respect to the posi-

tion of the wick in the lighter, then move said cover laterally outwards to its open position and then rotate said friction wheel to cause the production of an igniting spark.

2. In a pyrophoric lighter having an inflammable wick and a pyrophorous body, a cover enclosing said inflammable wick in the closed position of the lighter, a friction wheel bearing against said pyrophorous body, a movable actuating member, a rod connected with said cover, a 10 guiding pin carried by said rod and movable therewith, a tube enclosing at least a part of said rod and having a guiding slot formed therein, said pin extending through said slot, and a leverage system connecting said rod with said member and 15 said friction wheel and operable upon the actuation of said member to first raise said cover, then turn it outwardly to its open position and then rotate said friction wheel to cause the production of an igniting spark.

ARTHUR GOLDBERGER.
